UNITED STATES PATENT OFFICE.

LEWIS JOHNSTONE, OF BURY, ENGLAND, ASSIGNOR TO THE RADAX PNEUMATIC TYRE COMPANY, LIMITED, OF WARRINGTON, ENGLAND.

METHOD OF STRETCHING FABRIC FOR DETACHABLE COVERS OF PNEUMATIC TIRES.

SPECIFICATION forming part of Letters Patent No. 669,836, dated March 12, 1901.

Application filed May 22, 1899. Serial No. 717,787. (No specimens.)

To all whom it may concern:

Be it known that I, LEWIS JOHNSTONE, engineer, a subject of the Queen of Great Britain, residing at Deeply Vale, Bury, in the 5 county of Lancaster, England, have invented a certain new and useful Method of Stretching Fabric for the Manufacture of Detachable Covers for Pneumatic Tires, of which the following is a specification.

10 This invention relates to the method of manufacturing detachable covers for pneumatic tires from a self-shaped fabric—that is, a fabric which is curved or specially shaped in the weaving—viz., curved to the radius (or 15 thereabout) of the tire, when inflated, in respect of which such detachable covers are to be used.

Heretofore it has been proposed in patents of earlier date to employ a textile fabric (advantageously a woven cotton cloth or canvas of sufficient strength and resilience) formed somewhat V-shaped or U-shaped in cross-section and also curved in the direction of its 25 length to or about the radius of the tire to be made, such shaped fabric being woven or produced in any suitable manner.

According to the present invention such specially-shaped fabric is treated in the manner as follows: Two drums, reels, or rings 30 (which for the sake of brevity will hereinafter be referred to as "rings") are employed, advantageously of the diameter of the finished tire, but narrower in cross-section and mounted in the same plane. Two or more pairs of 35 such rings may be similarly mounted in one machine, the rings in each pair being arranged in the same plane. Between each pair of rings and in the same plane therewith is arranged a small drum, reel, roller, or 40 ridge, (which may either be formed in one piece or of a number of parts,) hereinafter referred to as the "roller." This roller is advantageously an idle roller and is adapted to be adjusted in any desired direction in relation to its pair of rings. The said rings (or 45 one of them) may be adapted to be independently adjusted toward and away from one another or from the roller or in any other desired direction, the object of which adjustment will be hereinafter explained. One end 50 of a length of the specially-shaped fabric is secured to one of the rings, (which I will hereinafter term the "brake-ring,") and such

length of fabric is wound thereon. The other end of the length of fabric is led from the 55 brake-ring over the roller and thence to the second ring, (which I will hereinafter term the "winding-ring,") to which latter it is firmly secured. A suitable brake or drag or 60 retarding action is put upon the brake-ring, while the winding-ring is revolved by any suitable means by preference very slowly. The roller, which is preferably of convex 65 form, is so adjusted with respect to the two rings (or one or other of the rings) is so adjusted with respect to the roller) that as the fabric is dragged off the brake-ring it will be inverted or turned inside out as it passes over the roller and turned back again or re-inverted between the roller and the winding- 70 ring, while at the same time the fabric is in very great tension and is strongly stretched during such circuitous passage from the brake-ring to the winding-ring, on which latter the stretched fabric is wound and thereafter employed for the purpose of manufacturing the detachable covers for pneumatic 75 tires in any suitable or desired manner. Before removing the stretched fabric from the winding-ring and before the tension is released the fabric is clamped or secured in any 80 suitable manner on the winding-ring and removed from the machine, and the fabric still on the ring is subjected to the action of wet steam and dried or treated in any other desired manner. It can, for instance, be immersed in a bath and dried or mercerized and 85 washed and dried. India-rubber can also be applied to the fabric prior to the stretching and winding process, if so desired. 90

By this invention fabric of the kind described can be readily stretched in one operation—that is, a sufficient amount of the stretch can be taken out of the same to render same inextensible or sufficiently so to prevent the detachable outer cover made therefrom from coming off the rim when inflated under ordinary riding pressures. 95

In order that this invention may be the more easily understood and readily carried 100 into practice, I will proceed to further describe the same with reference to the drawings hereunto annexed, which illustrate means for carrying out the method which forms the subject-matter of the present application. 105

Figure 1 is a front view of a stretching-machine according to the present invention. Fig. 2 is a sectional view thereof looking in the direction of the arrow 2, Fig. 1. Fig. 3 is a view, partly in section, looking in the direction of the arrow 3, Fig. 1. Fig. 4 is a local vertical sectional view on line 4-4, Fig. 1, showing the mechanism for holding and adjusting the intermediate roller 2. Fig. 5 is a diagrammatic view showing the fabric inverted on the roller 2 as it is drawn off the ring 1 and again inverted as it is wound on the ring 19. Fig. 6 is a separate view of the said ring 19, showing means by which same is rendered collapsible, though, as hereinbefore described, the winding-ring may in part of the operations be a solid and not a collapsible ring. Fig. 7 is a vertical sectional view thereof on line 7-7, Fig. 6. Figs. 8 to 11 illustrate a modified arrangement, and Figs. 12 to 15 another modification, and Fig. 16 still another modification, as hereinafter described.

The machine illustrated in Figs. 1 to 7 is double-sided—that is, is a double machine—the operation on either side being the same. In the arrangement illustrated in said Figs. 1 to 7 the end of a length of the special fabric is firmly fixed to the brake-ring 1, and said fabric is then wound upon said ring 1. The ring 1 is fixed on the axle A, on which latter is also fixed the band-brake wheel 2. The axle A is journaled in the adjustable bearing or carriage a, which is adapted to slide upon the supporting bars or rods b, carried on the main frame or base c of the machine, the said bearings or carriage a being adjusted by means of the adjusting-screw 3. (See Fig. 3.)

5 indicates hand-brakes which act on brake-wheels 2.

6 is an adjustable mount or carriage, on which are carried or mounted the small rollers 7, one such roller only being shown in Fig. 4. The said mount is adapted to slide upon the fixed rods b and can be adjusted thereon by means of the adjusting-screw 8. (See Figs. 3 and 4.) The roller 7 is an idle roller on the shaft 9, journaled in the forked arms 10 of the support 11. The shaft 9 is adjustable in the direction of its length by means of the screw-nut 12 thereon. The mount 11 is carried in the arms 13 and 14 of the mount 6 and can be adjusted vertically and turned upon its vertical axis. The vertical adjustment is obtained by means of the screw-sleeve 15, which screws through the internally-screw-threaded lower socket 14. The upper part of the spindle 11 has fixed thereon a worm-wheel 16, with which gears a worm 17, which can be rotated by the square end 18 on its shaft.

19 indicates the winding-rings, one on each side of the machine, which are fixed rigidly on the shaft B, which is journaled in the bearings or carriage d, fixed to the frame c of the machine. On the shaft B is the worm-wheel 20, loosely mounted and driven by the worm 21

on the worm-shaft 22, which carries the driving-pulleys 23, driven in any suitable manner. The worm-wheel 20 carries rigidly fixed thereto the crank pinion or spindle 24, on which rotate the pinions 25 and 26, these two latter being cast or otherwise formed together.

27 is a stationary toothed wheel keyed or otherwise fixed to the boss d' of the carriage d.

28 is a toothed wheel keyed or otherwise rigidly fixed to the shaft B aforesaid. Thus it will be seen that as the worm-wheel 20 revolves it carries around the double pinion 25 26, the pinion 25 gearing with the stationary toothed wheel 27, and consequently the pinion 26 is thereby revolved, and this latter in turn revolves the toothed wheel 28, which being fixed to the axle B consequently will 85 very slowly revolve the latter, and thus the speed is geared down and a very slow and steady rotation of the rings 19 is obtained. These rings 19 (when same are to be used as the mandrel on which the tire is to be built up 90 and finished) are formed of segments hinged together, as at 29^a and 29^b, and one of such segments is cut through diagonally, as at 29^c, and provided with a clamping device 29^d, the mandrel being thus made collapsible, as shown 95 in Figs. 6 and 7, with a central frame 29, having three or other suitable number of arms, one arm of which is extensible by means of the internally-screwed nut or adjusting device 30, through which screws the screwed part 31 of the rod 32, by means of which latter the frame 29 may be given an expandable effect for the purpose of expanding the ring 19, and it can be tightly pressed and locked 100 against the inner circumference of the collapsible ring 19, and thereby hold the same rigid, while when it is desired to collapse the ring this can be easily effected, as will be readily understood from the drawings. For instance, when the stretched fabric is wound 110 upon the ring 19 and there finished to form the finished cover such ring 19 must be collapsed to enable such finished cover to be removed therefrom.

Referring to Figs. 1, 2, and 3, the band-brake 5 (the ends of which are provided with a screw-bolt 33 and nut thereon by which to vary the tightness of said band-brake 5 upon the brake-wheel 2) has an extension 34, to the upper end of which latter is pivoted a rod 120 35, which is connected to a dynamometer 36 or other suitable indicator or spring-balance. The latter is mounted on the framing or support 37, mounted on the fixed carriage d, so that any desired amount of brake or retardation can be put upon the brake-wheels 2, and consequently upon the rings 1, fixed on the shaft A, and at the same time the strain put upon the fabric is registered or indicated and can be readily seen upon the dynamometer. 130 x is the fabric to be stretched. Means are provided for readily mounting the rings 1 upon the shaft A or removing the same therefrom, and similar means are used for mount-

ing the rings 19 upon the shaft B. The rings 1 and 19 are narrow in cross-section, with a suitable circumferential edge, the rings being preferably made with parallel sides and 5 rounded edges. By altering the contour of the roller 7 and altering its position relatively to the rings 1 and 19, either or both, the stretch on different parts of the width of the fabric can be varied. In place of this roller 7 10 a fixed convex surface or ridge of any suitable shape may be employed.

The operation is as follows: The fabric x is secured to and wound upon ring 1 and is led around the roller 7 and the end secured 15 to and wound upon the winding-ring 19. The ring 1 is adjusted toward or away from the ring 19, as desired, and the roller 7 adjusted in any direction required and the brake-band 5 tightened up upon the brake-wheel 2, so as 20 to put the desired amount of strain upon the fabric x. For example, it has been found in practice that with a curved fabric of the character described, showing a breaking strain of, say, four hundred pounds to four hundred and 25 fifty pounds, or thereabout, on the dynamometer, if the strain put upon said fabric in stretching same (according to this invention) is made to indicate, say, one hundred and fifty pounds to one hundred and sixty pounds on 30 the dynamometer 36 then such fabric will be rendered inextensible or sufficiently so (for the purposes stated) after same has been stretched on the winding-ring, as hereinafter 35 described. The shaft B and rings 19 thereon are then very slowly rotated, and the fabric is drawn off the ring 1 over the roller 7, on which it is inverted, and thence wound onto the ring 19 and inverted a second time as it is wound 40 on the latter, and in this manner the fabric is in one operation stretched to such a degree as to render same practically inextensible for the purpose of forming the detachable covers of pneumatic tires, as aforesaid. The roller 45 is manipulated by the worm-wheel while winding to guide the fabric.

The machine may be used as a stretching machine pure and simple. In that case the brake-ring 1 and the winding-on ring 19 are 50 both solid. The fabric to be stretched is wound on the brake-ring 1, one end being fastened to it. The other end of the fabric is fastened to the winding-on ring, and the fabric is then wound onto the said winding-on ring 55 under great tension. When a sufficient length of the fabric has been thus wound onto the winding-on ring—say, two or three laps—the fabric is clamped to the ring while still under tension, and the ring may then be removed 60 from the machine. If now the fabric were removed from the ring, it would spring back; but the stretch is permanently removed by the fabric being steamed while clamped under tension. This steaming puts such strain 65 on the fabric that after being dried while still clamped on the ring 19 the fabric will no longer spring back when the clamp is released.

Instead of steaming the fabric while stretched on the ring the fabric may be mercerized or treated in any suitable bath and 70 then dried before being released from the ring, or the fabric may be made wet before it is stretched and then when stretched and clamped on the ring allowed to dry there; but steaming has been found in practice to 75 have many advantages.

The machine above described may be used for making up tires from already-stretched fabric in the following manner: A length of the stretched fabric, rubbered first to a sufficient extent, is wrapped on the brake-ring and wound under slight tension onto the winding-on ring, which in this case must be made collapsible. If the completed tire is to consist of more than one thickness of fabric, 85 (which is in most cases preferred,) slight tension only is used after a sufficient thickness of fabric has been wound on the ring, and when dried the ring is collapsed and the tire removed from the ring. 90

I may also use my improved apparatus for the manufacture of tires in the following manner: The unstretched fabric, fully or partially impregnated with rubber, may be placed on the brake-ring and wound onto the winding- 95 ring under great tension and there clamped. Whether the fabric has been fully or only partially impregnated with rubber it must while still clamped on the winding-ring be steamed and dried. If the fabric has been 100 fully rubbered in its unstretched condition and is placed in that condition on the brake-ring, it may be thence at once wound under great tension onto a collapsible winding-on 105 ring and stretched and finished in one winding operation.

Referring now to the modification shown in Figs. 8 to 11, instead of using a rotatable roller 7, as shown in Figs. 1 to 5, to convert the fabric a fixed block, horn, or ridge e may 110 be used for the same purpose. Fig. 8 is a plan of a suitably-shaped block. Fig. 9 is a longitudinal section thereof on line 9 9, Fig. 8; Fig. 10, an end view of the block e, and Fig. 11 a local diagrammatic view (after the manner of Fig. 5) showing the block e fixed in position between the unwinding-ring 1 and the winding-ring 19. The said block e is recessed and undercut at each end at f, as shown in Figs. 8 and 9, so that rounded ends project at each of the four corners e' of said block e, the object of this construction being that the undercut recess f enables the block e to fit over without touching the rings 1 and 19, respectively, so that the rounded corners or 120 projections e' on said block e fit into and support the fold of the fabric x as same is being inverted while passing from the unwinding-ring onto the block e and again to fit into and support the fold of the fabric x as same is being reinverted while being drawn off the fixed block e onto the winding-ring 19. The fabric x thus slides over the block e, the rubber contact-surface of which latter is smooth, 125 130

and by tilting the block *e* or altering the position of same relatively to the ring 1 or ring 19, or both, the stretch can be taken out of the fabric either evenly right across its width 5 or more stretch can be taken out of the fabric at one point than at others, means being provided to support and adjust said block *e* in a similar manner to those shown for supporting the roller 7, (see Figs. 1 and 4,) or 10 the block *e* may be supported and adjusted in any position by any suitable means, as will be readily understood and need not therefore be further described here.

Instead of winding the fabric on the brake-ring 1 have in Figs. 12 to 15 shown how this apparatus can be used so as to enable the fabric to be stretched continuously from the "batch" or continuous bobbin. Fig. 12 is a diagrammatic view showing how the apparatus would then be worked. An additional fixed block *g* (shown in detail in Figs. 13 to 15) may be usefully employed in guiding the fabric from the stock-bobbin onto the brake-ring. Fig. 13 is a plan of a suitable block *g*; 25 Fig. 14, a longitudinal sectional view on line 14-14, Fig. 13; and Fig. 15, an end view there-of looking in the direction of the arrow 15, Fig. 13. The bobbin of material *i* may advantageously be mounted over the brake-ring 1, 30 and instead of fixing the fabric to this ring, as previously described, the surface should be roughened or provided with pins or equivalent arrangement to prevent the material *x* from being dragged over the brake-ring 1 at a 35 speed quicker than the brake-ring 1 is allowed to revolve. From the brake-ring 1 the material passes to the winding-ring over a similar block *e* and in a similar manner to the arrangement previously described with reference to Figs. 8 to 11.

A convenient form for the block or shoe *g* as employed in Fig. 12 is shown in Figs. 13, 45 14, and 15. The block is formed with an undercut recess *h*, (similar to the recess *f* in the block *e*,) so as thus to form projecting rounded corners *g'* (similar to the corners *e'*) at one end only. The other end *g²* of the shoe *g* is slightly rounded in a convex manner, so as to pass the cloth *x* coming from the bobbin *i* 50 over the convex end *g²* onto the shoe *g* and thence onto the ring 1, the cloth being inverted as it passes from the shoe *g*.

Fig. 16 is a diagrammatic view illustrating an arrangement similar to that shown in Fig. 55 12, except that the brake-ring 1 instead of revolving has a brake-shoe *m* applied directly to the fabric, which is dragged between the brake-block *m* and the ring 1, so that the fabric is thus held back or retarded and consequently stretched as it is drawn by and wound onto the winding-ring 19. This brake-block *m* may be applied in any suitable manner to the ring 1 and by any suitable means—as, for instance, by means of the brake-lever *n*, turning about the fulcrum *o*, this lever being weighted at *p*, so that according to the leverage and weighting of the lever *n* any desired 60 65

pressure or braking action can be obtained. No dynamometer or separate band-brake wheel will then be required.

Having now particularly described and ascertained the nature of this said invention and in what manner the same is to be performed, I declare that what I claim is—

1. The herein-described method of manufacturing detachable covers for pneumatic tires from curved woven fabric consisting of winding said fabric into a ring under great tension, holding said fabric against contraction and while so held subjecting said fabric 75 to the action of steam, then drying the fabric before releasing same whereby the fabric is rendered practically inextensible in the direction of its length substantially as and for the purposes hereinbefore described. 80

2. The herein-described process of manufacturing detachable covers for pneumatic tires from curved woven fabric consisting in winding said fabric in superposed layers into a ring under great tension, holding said fabric against contraction and while so held subjecting said fabric to the action of steam, then drying the fabric before releasing same whereby the fabric is rendered practically inextensible in the direction of its length substantially as and for the purposes hereinbefore described. 85 90

3. The herein-described method of manufacturing detachable covers for pneumatic tires from curved woven fabric which consists 100 in passing the fabric under tension over a succession of convex surfaces so arranged as to invert and reinvert the curvature of the fabric; winding said fabric into a ring under great tension; holding said fabric against contraction and wetting the said fabric while so held; and drying the fabric before releasing the same, substantially as described. 105

4. The herein-described method of manufacturing detachable covers for pneumatic 110 tires from curved woven fabric, which consists in passing the fabric under tension over a succession of convex surfaces arranged to invert and reinvert the curvature thereof; winding the said fabric into a ring under great tension; subjecting the fabric to the action of wet steam; and drying the said fabric while still held under tension, substantially as described. 115

5. The herein-described method of manufacturing detachable covers for pneumatic 120 tires from curved woven fabric, which consists in passing the fabric under great tension over a succession of convex surfaces so arranged with relation to each other as to invert and reinvert the curvature of the fabric, winding 125 said fabric into a ring under great tension, subjecting said fabric to the action of wet steam, and drying the fabric while held under tension, substantially as described.

LEWIS JOHNSTONE.
